H. WELLS

FORM FOR CONCRETE CONSTRUCTION

Filed July 18, 1923

Inventor

HEWITT WELLS.

By *Frank P. Maguire*
Attorney

UNITED STATES PATENT OFFICE.

HEWITT WELLS, OF WASHINGTON, DISTRICT OF COLUMBIA, ASSIGNOR TO WASHINGTON STEEL FORM COMPANY, OF WASHINGTON, DISTRICT OF COLUMBIA, A CORPORATION OF THE DISTRICT OF COLUMBIA.

FORM FOR CONCRETE CONSTRUCTION.

Application filed July 18, 1923. Serial No. 652,232.

To all whom it may concern:

Be it known that I, HEWITT WELLS, a citizen of the United States, residing at Washington, in the District of Columbia, 5 have invented certain new and useful Improvements in Forms for Concrete Construction; and I do hereby declare the following to be a full, clear, and exact description of the invention, such as will enable 10 others skilled in the art to which it appertains to make and use the same.

In Letters Patent No. 1,445,374 of February 18, 1923, I have shown and described the manner of constructing reinforced concrete floor slabs and walls by the use of steel form plates of special design laid between falsework of wood joists, the steel plates being supported along their edges by narrow wood strips previously nailed to the 15 sides of the joists, these plates or forms being readily removed from below after the concrete slab has sufficiently set, the strips on the sides of the joists being first ripped off. The joists are left undisturbed and 20 support the slab and load above permitting rapid re-use of the steel plates and obviating the necessity of providing large quantities of such plates.

My present invention relates to certain 30 improvements in the design of the metal forms such as are used in the construction described in my before noted Letters Patent. The use of these forms on a larger number 35 of building operations has resulted in a considerable saving in lumber and in time of erection over previously known methods, and by experiments and such extensive use 40 the details of the structural design of the forms have been improved so as to permit their use with the greatest economy of labor and a maximum efficiency.

In the drawings, Figure 1 is a view in perspective of my improved form showing it in overlapped relation with a second form 45 which is partly broken away. Figure 2 is a longitudinal sectional view of two forms. Figure 3 is a cross sectional view showing the arrangement of the forms between supporting joists.

As shown, my improved form is a metal 50 plate 1 bent downwardly at its sides as at 2 and then inwardly as indicated at 3. Each

of these portions is of the same length as the plate of which it is a part, but the end 4 is cut away so that in positioning a series 55 of the plates appropriate overlapping may be secured without interference. Each of the plates is of slightly greater width at that end where its sides are cut away than at its other end so as to allow of the necessary 60 lapping. To provide the necessary stiffening and prevent sagging of the form plates under the weight of the wet concrete each plate is provided with braces 5 which extend transversely between the downwardly 65 bent sides of the form and are in spaced arrangement along its length, each end of each brace being slightly beveled so as to tightly fit between the sides. It is manifest that the braces must be of varying lengths. 70 The braces may be held in position by indenting or punching in the metal of the downwardly bent sides from the outside sufficiently to slightly penetrate the ends of the braces or stiffeners as shown at 6. In 75 arranging the braces in position I place one flush with that end of the form which is to be overlapped by the next adjacent plate so that there will be a rigid support for such overlapping end, it being manifest that no 80 brace can be placed at the end of a form which is to lie over an adjacent form.

It is sometimes desirable, as when the forms are used to support thick and heavy slabs, that the plates be slightly arched and 85 this is effected by cutting the braces or stiffeners 5 with a slight crown at the center as shown at 7.

The form which I have herein described is readily adapted for use in the construction of flat concrete floor slabs, walls or the 90 sides of beams and columns, and is so designed that it can be lapped to fit any span, an arrangement especially advantageous in making provision for the extension of pipes 95 through a floor, the forms being shifted back on either side of the pipes, and the space through which these pipes extend being filled by a wood filler.

I claim as my invention:

1. A form for concrete construction comprising a metal plate having its sides bent downwardly and then inwardly, a portion of each side being cut away near one end to

permit overlapping with the next adjacent form, and a series of transversely arranged braces fitted between said downwardly extending sides and means for permanently 5 fastening the braces in position.

2. A form for concrete construction comprising a metal plate having its sides bent downwardly and then inwardly, a portion of each side being cut away near one end to 10 permit overlapping with the next adjacent form, and a series of transversely arranged braces fitted between said downwardly extending sides, the metal of the sides of the plate being indented to engage the ends of 15 said braces.

3. A form of concrete construction comprising a metal plate having its sides bent downwardly and then inwardly, a portion of each side being cut away near one end to 20 permit overlapping with the next adjacent

form, and a series of braces slightly crowned at the center and fitted between said downwardly extending sides.

4. A form for concrete construction comprising a metal plate having its sides bent 25 downwardly and then inwardly, said plate being slightly wider at one end than the other, that portion of each side at the widest end of said plate being cut away to permit overlapping of the plate with the next adjacent form, and a series of braces fitted between the downwardly extending sides of 30 said metal plate and slightly crowned at the center, the metal of the sides of the plate being indented to engage the ends of 35 said braces.

In testimony whereof I have signed this specification.

HEWITT WELLS.
